US0D1032621S

(12) **United States Design Patent** (10) Patent No.: **US D1,032,621 S**
(45) Date of Patent: ** Jun. 25, 2024

(54) **DISPLAY PANEL WITH GRAPHICAL USER INTERFACE**

(71) Applicant: **LG ELECTRONICS INC.**, Seoul (KR)

(72) Inventors: **Junghwan Lee**, Seoul (KR); **Hoil Jeon**, Seoul (KR); **Sojin Park**, Seoul (KR); **Eunyoung Chee**, Seoul (KR); **Nerry Son**, Seoul (KR); **Hyewon Kim**, Seoul (KR)

(73) Assignee: **LG ELECTRONICS INC.**, Seoul (KR)

(**) Term: **15 Years**

(21) Appl. No.: **29/752,048**

(22) Filed: **Sep. 24, 2020**

(30) **Foreign Application Priority Data**

Mar. 30, 2020 (KR) 30-2020-0014082

(51) **LOC (14) Cl.** **14-04**

(57)

CLAIM

The ornamental design for a display panel with graphical user interface, as shown and described.

DESCRIPTION

The sole FIGURE is a front view of the display panel with graphical user interface showing our new design.

The broken lines depict portions of the display panel with graphical user interface that form no part of the claimed design.

1 Claim, 1 Drawing Sheet
